UNITED STATES PATENT OFFICE.

JOHN VAN VLECK AND WILLIAM N. STEVENS, OF NEW YORK, N. Y.

GLOWER-SUPPORTING PLUG FOR ELECTRIC LAMPS.

SPECIFICATION forming part of Letters Patent No. 672,607, dated April 23, 1901.

Application filed April 27, 1900. Serial No. 14,523. (No model.)

To all whom it may concern:

Be it known that we, JOHN VAN VLECK and WILLIAM N. STEVENS, of the city of New York, State of New York, have invented a new and useful Improvement in Glower-Supporting Plugs for Electric Lamps, of which the following is a specification.

Our invention relates to that type of electric lamp in which there is a glower normally non-conducting, but which becomes conducting and caused to glow upon being raised to a certain temperature.

Our invention consists more particularly in the glower-supporting plug of non-conducting material having a glower permanently secured upon one face thereof and provided with circuit connections for said glower, the same forming in its entirety a new article of manufacture and sale, and also in the construction of said plug, as more particularly pointed out in the claims.

In the accompanying drawings, Figure 1 is a vertical cross-section of our improved glower-supporting plug. Fig. 2 is a side elevation showing also a modification in which the reflecting-surface is made conical or convex instead of concave, as shown in Fig. 1. Fig. 3 is a vertical cross-section showing a modification of Fig. 1, wherein the glower is made curved to conform to the concavity of its support.

Similar letters of reference indicate like parts.

A represents a body of non-conducting material, such as plaster, which is incased in a metal shell B, which is screw-threaded to enable it to be readily inserted in a threaded socket in the lamp. The lower part F of the body A, as shown in Fig. 1, is of larger diameter than the upper part G and is provided with a curved or inclined reflecting-surface C. On the upper side of the body A is a metal contact-plate D. The glower E, of refractory material, is supported in any suitable way in front of the reflecting-surface C, and when said surface is concave, as shown in Fig. 1, said glower is disposed wholly within said concavity. One circuit-wire a is connected to the contact-plate D and to one end of the glower. The other circuit-wire b is

connected to the other end of the glower and to the metal shell B. It will be readily understood that this arrangement provides for a current passing from the source of electricity to the main contact-plate D, to circuit-wire a, to the glower E, circuit-wire b, metal shell B, and so to the return-conductor.

The construction shown in Fig. 1 we regard as preferable, because there are no projecting parts liable to break off.

In the modification shown in Fig. 2 the lower face of the plug A is made conical or convex and the glower is supported below the apex of the same by its circuit-wires, as shown. The glower may be bent or curved, as shown in Fig. 2, to correspond to the form of the reflecting-surface. This arrangement obviously permits the light rays from the glower to be distributed over the larger portion of the sphere of illumination. In either case, however, the surface of the convexity or concavity acts as a reflector for the light, and if of plaster it may be left white, or, if desired, it may be suitably silvered.

The object of making the lower portion F of the body A of larger diameter than the upper portion is to afford a larger reflecting-surface and to permit of the whole glower being placed within the concavity when said reflecting-surface is concave, as shown in Fig. 1.

We claim—

1. As a new article of manufacture, a cylindrical plug of insulating material having at one end a circular face, a glower supported upon said plug in proximity to said face, and contact-pieces on said plug electrically connected to said glower, substantially as described.

2. As a new article of manufacture, a cylindrical plug of insulating material having at one end a concave circular face, a glower supported upon said plug in proximity to said face and contact-pieces on said plug electrically connected to said glower, substantially as described.

3. A glower-supporting plug for electric glower-lamps having an interior body of non-conducting material, an inclosing metallic shell threaded on its periphery, a curved or inclined reflecting lower portion and a glower

supported in front of said reflecting lower portion, and circuit connections, substantially as described.

4. A glower-supporting plug for electric glower-lamps having an interior body of non-conducting material, an inclosing metallic shell threaded on its periphery, a reflecting concavity in its lower portion, a glower supported on said plug and wholly within said concavity, and circuit connections, substantially as described.

5. A glower-supporting plug for electric glower-lamps having in its lower portion a concavity and a glower supported wholly within said concavity, substantially as described.

6. A glower-supporting plug for electric glower-lamps having a cylindrical body of non-conducting material, of enlarged diameter at one end, an inclosing metallic shell threaded on its periphery along its portion of smaller diameter, a curved or inclined reflecting portion on the face of larger diameter of

said body and a glower supported on said plug and in front of said reflecting portion, substantially as described.

7. A glower-supporting plug for electric glower-lamps having at its lower portion a curved or inclined reflecting surface and a glower supported in front of said surface and bent or curved in substantial correspondence thereto, substantially as described.

8. A glower-supporting plug for electric glower-lamps of non-conducting material, means for detachably connecting said plug to a lamp or fixture, and a glower supported on one face of said plug, and circuit connections for said glower embedded in the substance of said plug and secured to metallic contact-plates on the outer surface thereof, substantially as described.
